UNITED STATES PATENT OFFICE.

ELIHU N. KLEINBAUM, OF BROOKLYN, NEW YORK.

PAY-AS-YOU-ENTER DOOR.

1,022,684.

Specification of Letters Patent.

Patented Apr. 9, 1912.

Application filed January 3, 1911. Serial No. 600,432.

To all whom it may concern:

Be it known that I, ELIHU N. KLEINBAUM, a citizen of the United States, residing at Brooklyn, in the county of Kings and State 5 of New York, have invented certain new and useful Improvements in Pay-as-You-Enter Doors; and I do hereby declare the following to be a full, clear, and exact description of the invention, such as will enable others skilled in the art to which it 10 pertains to make and use the same, reference being had to the accompanying drawings, and to characters of reference marked thereon, which form a part of this specification.

The present invention relates, generally, to improvements in "pay-as-you-enter" doors, gateways, turn-stiles, and the like; and, the invention has reference, more particularly, to a construction of normally 20 locked door or turn-stile which is released from its locked condition by the deposit of a coin, so as to permit the entrance of a person therethrough.

The invention has for its principal object 25 to provide a "pay-as-you-enter door" or turn-stile which is of such a construction, that it is maintained in a normally locked condition, from which condition the same 30 can only be released by the deposit of a proper coin, representing the fee or charge required for entrance therethrough.

A further object of the present invention 35 is to provide an automatic locking and releasing mechanism for said "pay-as-you-enter" door or turn-stile, the operations of the said releasing or unlocking mechanism thereof being coin-controlled.

Other objects of the present invention not 40 at this time more particularly enumerated, will be clearly understood from the following detailed description of the present invention.

With the various objects of the present 45 invention in view, the said invention consists in the general arrangements and combinations of the devices and parts, as well as in the details of the construction of the same, all of which will be hereinafter more 50 fully set forth, and then finally embodied in the clauses of the claim which are appended to and which form an essential part of this specification.

The invention is clearly illustrated in the 55 accompanying drawings, in which:—

Figure 1 is an elevation of the novel con-

struction of "pay-as-you-enter" door or turn-stile and its automatic coin-controlled locking and releasing mechanism, the same being made according to and embodying the 60 principles of the present invention. Fig. 2 is a semi-diagrammatic detail view combining therein vertical cross-sections of the automatic locking and releasing mechanism of the "pay-as-you-enter" door or turn-stile 65 and the coin-controlled device connected therewith, together with the system of electrical wiring for operatively connecting the same, said view being drawn upon an enlarged scale. Fig. 3 is a horizontal section 70 taken below the door or turn-stile member and the floor-plate, looking in a downward direction. Fig. 4 is a large detail cross-section of a circuit-closing mechanism for operating said coin-controlled device, to release the coin from its operative relation therewith, whereby the main electrical circuit is broken, and the locking mechanism of the door or turn-stile is returned to its normal locking condition; and Fig. 5 is a transverse section of the same, taken on line 5—5 80 in said Fig. 4.

Similar characters of reference are employed in all of the above described views, to indicate corresponding parts.

Referring now to the several figures of the drawings, the reference-character 1 indicates a suitable frame or gateway in which is located the "pay-as-you-enter" door or turn-stile. Said "pay-as-you-enter" 90 door or turn-stile may be constructed in various ways or styles. As shown in the accompanying drawings, the "pay-as-you-enter" door or turn-stile comprises a vertical central shaft 2, journaled at one end in 95 a suitable bearing 3 which is connected with said frame 1, and in a suitable bearing-portion 4 of a floor-plate 5 which is arranged beneath said door or turn-stile, and covers a floor-pit 6. The lower end of said shaft 2 is journaled in a thrust bearing block 7, which is secured upon the bottom of said floor-pit 6, and secured upon said shaft 2, in any suitable manner, are a plurality of radiating door or stile-members 8, of any 100 desirable form or construction. Secured upon said shaft 2, beneath said floor-plate 5, by means of a key 9, or any other suitable fastening means, is a lock-disk or wheel 10, which is provided in its circumferential 105 portion with a plurality of bolt-receiving grooves or spaces 11, corresponding in num-

ber and position to the said radiating door or stile-members 8 connected with and extending from the upper portion of said shaft 2. Secured upon said shaft 2, preferably 5 beneath said lock-disk or wheel 10, by means of a key 12, or any other suitable fastening means, is a ratchet-wheel 13, the same being provided with suitably disposed teeth 14. The said thrust-bearing block 7 10 is provided with a suitably located and upwardly extending boss or block 15, provided with a stud-pin 16 upon which is pivotally mounted a pawl 17, said pawl being adapted to engage said teeth 14 of said 15 ratchet-wheel 13, whereby said "pay-as-you-enter" door or turn-stile is permitted to be turned only in a proper direction. Said boss or block 15 is further provided with a lug 18 having a receiving socket for seating 20 therein a spring-member 19, which bears against the pawl 17 and maintains the latter in its operative relation with said ratchet-wheel 13. Secured within said floor-pit 6, in any desirable location and manner, are a 25 pair of solenoid-coils 20, and further arranged within said floor-pit 6, so as to be located opposite the free ends of said solenoid-coils 20, are pairs of standards 21 which are provided with suitable bearing- 30 portions 22 for slidably supporting the armatures 23 of said solenoid-coils 20. The outer end of each armature 23 is formed to provide a locking bolt 24, provided with an anti-friction roller 24', the same being 35 adapted to normally enter one of said bolt-receiving grooves or spaces 11 of said lock-disk or wheel 10, and thereby engaging the latter so as to prevent the turning or revolving of the door or turn-stile until said 40 locking-bolt is released or retracted from said engagement. Arranged about each of said armatures 23, between the bearing-portions 22 of said standards 21, is a spring-member 25 which bears at one of its ends 45 against one of said bearing-portions 22, and at its other end against a suitable stop secured to said armature, such as the transverse pin 26. The tension or pressure of said spring-members 25 tends to maintain 50 said armatures 23 and their locking bolts 24 in their normal positions so as to cause the bolts to engage with said lock-disk or wheel 10 in the locking relation herein-above described. 55 Secured in a suitable position adjacent to said "pay-as-you-enter" door or turn-stile is a coin-receiving device adapted to receive a coin and thereupon cause the operation of the mechanism for releasing said door or 60 turn-stile from its locked or immovable condition. Said coin-receiving device comprises a suitable casing 27 provided with a coin-chute 30 which delivers a coin to a circuit-closing mechanism which is arranged 65 within said casing 27, the same being con-

structed and operated as follows:—Secured to the inner side of said casing 27, and suitably insulated thereupon, is a bracket-member 40 which is provided in its free end with a coin-receiving space or cut-out portion 41, 70 the same being presented in a proper position so as to register beneath the outlet-mouth or end 42 of said coin-chute 30. Secured upon the opposite and interior side of the said casing 27, and in alinement with said bracket-member 40, is a solenoid-coil 43. Supported upon a partition-member 44, within said casing 27, so as to be located opposite the free end of said solenoid-coil 43, are a pair of standards 45, provided with 80 bearing-portions comprising sets of roller-bearings 46 for slidably supporting an armature 47. The outer end of said armature 47 is provided with an enlarged portion 48 having in its free end a coin-receiving space or cut-out portion 49 which registers opposite said coin-receiving space or cut-out portion 41 of said bracket-member 40, and beneath the outlet-mouth or end 42 of said coin-chute 30. The said respective 85 coin-receiving spaces or cut-out portions 41 and 49, and the respective members in which they are formed, are electrically and physically separated from each other, but the former are designed to conjointly receive 90 a proper coin after the same is delivered by the extension 33 of the coin-chute 30. Arranged about said armature 47, between one of said standards 45 and the free end of said solenoid-coil 43, is a spring-member 50 100 which bears at one of its ends against the free end of said solenoid-coil 43, and at its other end against a suitable stop secured to said armature, such as the transverse pin 51. The tension or pressure of said spring-member 50 tends to maintain said armature 47 and its coin-receiving portion in its normal position, ready for the reception of a coin. 105 To release the door or turn-stile locking mechanism, a coin of proper denomination is deposited in the mouth of said coin-chute 30, whereupon the coin is delivered to the respective receiving spaces or cut-out portions 41 and 49 of the bracket member 40 and said enlarged portion 48 of the armature 47. The coin thus received straddles said bracket-member 40 and said enlarged portion 48, bridging over the intervening space between said parts, which closes or completes an electrical circuit, whereby the 110 electric current is caused to pass from a battery 52, or other suitable source of electrical energy, through the conductor 53, to one of said standards 45, whence it passes into the armature 47 and its enlarged portion 48, 115 through the coin and into said bracket-member 40, from which the current enters a conductor 54 leading to a terminal of one of said solenoid-coils 20. Said solenoid-coils 20 are connected in series by the conductor 120 125 130

55, and the electric current is returned from the second of said solenoid-coils 20 to said battery 52, by means of a conductor 56. The coin having thus compelled or closed what 5 may be termed the main circuit, the said solenoid-coils 20 are caused to exert their attractive function upon their respective armatures 23, whereby the said armatures 23 are retracted from their normal positions, 10 and their respective locking-bolts 24 are thereby withdrawn from their holding or locking engagement with the said bolt-receiving grooves or spaces 11 of the lock-disk or wheel 10, thus permitting said "pay-as-you-enter" door or turn-stile to be revolved, 15 and the person seeking entrance therethrough may pass. As soon as the door or turn-stile is revolved by the ingoing person, the said lock-disk or wheel 10 is also revolved, 20 whereby said bolt-receiving grooves or spaces 11, from which said locking bolts 24 have been withdrawn, are carried beyond the line of movement of said locking bolts 24, and the circumferential surface of said 25 lock disk or wheel 10 is presented in said line of movement of said locking-bolts. At the same time, this revolving movement of the lock-disk or wheel 10 carries around a contact-block 57, which is one of a plurality 30 of similar contact blocks suitably secured upon the under side of the lock-disk or wheel 10, said contact-blocks 57 corresponding in number to the number of said bolt-receiving grooves or spaces 11, and each of 35 the same being arranged in proper location with relation to one of said bolt-receiving grooves or spaces. The said contact-block 57 operates to close a secondary electrical circuit, by being brought in contact with a 40 contact-receiving element arranged in said circuit. Said contact-receiving element comprises a suitable standard 58, preferably secured upon the floor or bottom of said floor-pit 6, and mounted upon said standard 45 58 is a pair of spring-contact-receiving members 59, which are suitably insulated from each other and from said standard 58 by means of suitably disposed insulating blocks 60. Each of said contact-receiving members 50 59 are provided with suitable retaining members, preferably, in the form of bolts 61 which are provided with nuts and washers 62, and secured upon the free ends of said bolts 61, in any suitable manner, are binding posts 63. The secondary electrical circuit, of which said contact-receiving element is a part, comprises a battery 64, or other suitable source of electrical energy, one pole 55 of said battery being connected by means of a conductor 65 to one of the terminals of the solenoid-coil 43, and the other terminal of said solenoid-coil 43 being connected by means of a conductor 66 to the binding-post 63 of one of the said contact-receiving members 59. The binding post 63 of the other 60 of said contact-receiving members 59 is connected by means of a conductor 67 to the other pole of the battery 64. As said contact-block 57 moves into contact with the respective contact-receiving members 59, the 65 said secondary circuit is completed, by bridging over the current from one contact-receiving member 59 to the other, through said contact-block 57. Said secondary circuit being thus completed, the solenoid-coil 70 43 is put in operation so that its attractive function is exercised upon said armature 47, and is thereby drawn away from its proximity to said bracket-member 40. This action removes the supporting influence of 75 said enlarged portion 48 from the coin, which thereupon falls. The coin being thus removed the main circuit, in which are the said solenoid coils 20, is interrupted or broken, and the attractive influence of the 80 same upon the armatures 23 is discontinued, whereby the latter are moved forward by their respective spring-members 25 until the said anti-friction roller 24' of the locking-bolt 24 brings up against the outer circumferences of said lock-disk or wheel. The 85 continued partial revolution of the door or turn-stile continues the movement of said lock-disk or wheel 10, which carries away from its engagement with said contact-receiving members 59, the said contact-block 57, and thereby breaks or interrupts said secondary circuit, whereby the attractive influence of the solenoid-coil 43 upon the armature 47 is discontinued, permitting said 90 spring-member 50 to return the same to its normal initial position, with its coin-receiving portion in proper relation to said bracket-member 40, ready for the reception 95 of another coin. A further partial revolution of another coin. A further partial revolution of said lock-disk or wheel 10 carries into the line of movement of said locking-bolts 24, successive bolt-receiving grooves or spaces 11, into which said locking bolts 24 are projected by the tension or pressure of 100 the respective spring-members 25, thus locking the door or turn-stile against further movement, until another coin is deposited in said coin-controlling device, as will be 105 clearly evident. 110

It will thus be clearly apparent, that the present invention presents a novel construction of locking and releasing mechanism which is automatically operated by means of a coin-receiving device. The passage of a person through the door or turnstile, and the consequent movement of said door or turn-stile, during such passage, operating to reset both the coin-controlled device and the locking elements, through the medium of 115 closing a secondary electrical circuit. 120

The present invention provides a "pay-as-you-enter" door or turn-stile adapted to be of great utility, and of such a construction as will permit the same to be used for 125 130

many purposes; the same being admirably adapted for use, for example, upon surface or other cars, in railway stations, in places of amusement and recreation, and in fact in all places to which entrance is barred except upon the payment of a prescribed fee.

I am aware that changes may be made in the various arrangements and combinations of the devices and parts as well as in the details of the construction of said parts, without departing from the scope of my present invention, as set forth in the foregoing specification and as claimed in the clauses of the appended claims. Hence, I do not limit my invention to the exact arrangements and combinations of the various devices and parts and details of construction as described in the foregoing specification, nor as disclosed in the drawings accompanying the same.

I claim:

1. In a pay-as-you-enter door or turnstile, the combination with a revolving door, of a lock-disk or wheel, said lock-disk or wheel being provided at its circumference with rectangular bolt-receiving openings, spring-actuated locking-bolts normally entering said bolt-receiving openings, an anti-friction roller connected with each locking-bolt, a rearwardly extending shank connected with each locking-bolt, solenoid coils, the shank of said locking-bolts forming the armatures of said solenoids and the same serving to withdraw said locking-bolts from their locking engagement with said lock-disk or wheel when said solenoids are excited.

2. In a pay-as-you-enter door or turnstile, the combination with a revolving door, of a lock-disk or wheel, said lock-disk or wheel being provided at its circumference with rectangular bolt-receiving openings, locking-bolts normally entering said bolt-receiving openings, an anti-friction roller connected with each locking-bolt, a rear-

wardly extending shank connected with each locking-bolt, standards for slidably supporting said shanks, a spring arranged with each shank and adapted to thrust the same forward to carry said locking-bolt into locking engagement with said lock-disk or wheel, solenoid coils, said shanks of said locking-bolts forming the armatures of said solenoids and the same serving to withdraw said locking-bolts from their locking engagement with said lock-disk or wheel when said solenoids are excited.

3. In a pay-as-you-enter door or turnstile, the combination with a revolving door, of a lock-disk or wheel, said lock-disk or wheel being provided at its circumference with rectangular bolt-receiving openings, locking-bolts normally entering said bolt-receiving openings, an anti-friction roller connected with each locking bolt, a rearwardly extending shank connected with each locking-bolt, standards for slidably supporting said shanks, a spring arranged with each shank and adapted to thrust the same forward to carry said locking-bolts into locking engagement with said lock-disk or wheel, solenoid coils, said shanks of said locking bolts forming the armatures of said solenoids and the same serving to withdraw said locking-bolts from their locking engagement with said lock-disk or wheel when said solenoids are excited, a ratchet wheel revolving with said revolving door, and a pawl coöperating with said ratchet-wheel to prevent said revolving door from being turned in the wrong direction, substantially as and for the purposes set forth.

In testimony, that I claim the invention set forth above I have hereunto set my hand this 30th day of December, 1910.

ELIHU N. KLEINBAUM.
